CLAIM

The design of the bucket edge contour, as shown and described.

DESCRIPTION

FIG. 1 is a perspective view of the preferred embodiment of a bucket edge contour in accordance with the invention.

FIG. 2 is a front view of the bucket edge contour shown in FIG. 1.

FIG. 3 is a side view of the bucket edge contour shown in FIGS. 1 and 2; and,

FIG. 4 is a bottom view of the bucket edge contour shown in FIGS. 1, 2 and 3.

The broken lines shown in the drawing figures are for illustrative purpose and form no part of the claimed design.
